GUSTAV A. MILLER, OF SEATTLE, WASHINGTON

GLIDER PROPULSION DEVICE

Application filed September 16, 1930. Serial No. 482,233.

My present invention relates to glider construction and operation and more particularly to a glider propulsion device.

Gliders may be generally referred to as 5 motorless aeroplanes and must rely for their sustaining force while in the air upon the action of air impinging upon the wings, much as an aeroplane maintains itself in flight. The methods of launching gliders is 10 varied and well known. Oftentimes, however, while in flight it is found that the air currents, either horizontal or vertical, which are required to maintain the flight of the glider will momentarily die out and the 15 glider will immediately begin to lose elevation. This is undesirable, first, it may necessitate a forced landing where no facilities are available and, secondly, as is quite common, the currents may die out for but a short 20 period and then come back as strong as ever. If some means is provided to assist the pilot in maintaining his elevation for a short period, the flight can then be resumed. It is to provide means for enabling a pilot to assist 25 his glider in maintaining its elevation that I have provided my device. Therefore:

The principal object of my object is to provide means whereby the pilot of a glider may manually assist his machine in maintaining 30 its elevation.

A further object is to provide means whereby under favorable conditions the pilot may manually supply the little additional effort required to launch his glider.

Other and more specific objects will be apparent from the following description taken 35 in connection with the accompanying drawings, wherein:

Figure 1 is a front view of my device as 40 installed upon a glider with the same in its normal position of use.

Figure 2 is a similar view with my auxiliary wings partially depressed.

Figure 3 is a fragmentary cross-sectional 45 view showing my control mechanism as it appears with my wings as in the position indicated in Figure 2.

Figure 4 is a side elevation of a glider with 50 my device in place with parts of the same

broken away to better illustrate the construction.

Figure 5 is a fragmentary cross-sectional view through one of my auxiliary wings.

Figure 6 is a transverse section through 55 one of my wings showing the shutter arrangement in its opened position and further illustrating its operating mechanism.

Figure 7 is a similar view showing my shutter closed and such parts of the glider as 60 are necessary to show the co-acting parts.

Figure 8 is a fragmentary cross-sectional view showing the control mechanism of my device, the same showing the wings in their 65 normal position.

Figure 9 is a view similar to Figure 8 with the wings partially depressed.

Figure 10 is a cross-sectional view taken along the line 10—10 of Figure 2.

Referring to the drawings throughout 70 which like reference characters indicate like parts, numeral 10 designates the main wing portion of any standard glider having the passenger receiving fuselage 12 and the necessary vertical rudder 14 and horizontal 75 rudder 16. Conveniently spaced below wings 10, and I have found 8 or 10 inches a convenient distance, are two wings 20 and 22, which are hingedly secured at 24 to a frame member 26. It will be noted in Figure 80

10 that the two hinged joints 24 are not parallel but converge to a point forward of the glider. Secured to the upper surface as at 85 28 of the wings is a tension spring member 30, which I prefer to secure to frame 26 by some adjustable means as by turn buckle 32.

The purpose of these two resilient members is to counter-balance the weight of the wings 20 and 22 and for this purpose any resilient 90 means might be used. A coil spring or rubber of the proper character is equally satisfactory. Wing members 20 and 22 I prefer to form as a frame work 34 to which are pivotably secured, as at 36, a plurality of shutter members. The exact shape of these shutter 95 members is relatively immaterial, although I have found it a little more satisfactory to use the form substantially as shown in Figures 6 and 7 wherein each member 38 is provided with a lip 40. This fits naturally over 100

the pivot point 36 when in the closed position and gives an impinging surface for the action of the air. In order to close shutter 38 I provide an operating bar 42 which is pivoted by a parallelogram arrangement from points 40 and 44 and has secured to it the shutter engaging member 46. The arm 48 which supports the leading end of bar 42 has a portion extending above pivot 44 which is adapted to engage an abutment 50 to the end of closing all the shutters at a single movement.

Any satisfactory means might be provided to give my auxiliary wings an up and down or flapping movement. I have illustrated particularly in Figures 8 and 9, a mechanism which I have found particularly adaptable to this use. This consists of a bell crank 52 which is pivoted to the fuselage at 54 and in turn has pivoted to it at 56 the arm 58 which in turn is pivotably secured at 60 to the wing 22. Pivotably secured at 62 is a link member 64, which in turn is pivotably secured to the cross bar 66, which may be a separate member as indicated, or may form a part of the vertically moveable member 68. The wide form of members 68 is best shown in Figures 3 and 4 wherein the two ends of member 68 are bent over and encircle vertically disposed post 70. These bent over portions serve as spring seats for the two compression springs 72 and 74. These springs may be termed buffers and, of course, could be replaced by rubber buffers. Their purpose is to slow up the end of either the upward or downward stroke and to steer the mechanism in the reverse direction. The sliding member 68 is connected by suitable linkage 76 with the long lever 78. Lever 78 is pivotably secured to the fuselage frame at 80 and has its forward end bent upwardly to provide the hand lever 82. This I have elected to provide with cross member 84 so that the convenient grips are provided so that both ends might be used at once if desired.

In the longitudinal sectional views 3 and 4 I have shown the conventional joy stick 86 and the foot lever 88, which form parts of the standard glider control mechanism and, of course, is no part of this present application.

Method of operation

In operating my device let us assume that the glider is in position on a field and that a head wind is blowing but which is not of sufficient intensity or strength so that the glider can lift itself. My auxiliary wings in this position will be as indicated in Figure 1. In this position lever 48 has contacted the abutment 50 and the shutters 38 are all in the closed position such as shown in Figure 7. The pilot then grips handle 84 which will then be in the position as indicated in Figure 4, and by pulling sharply to him will pull the auxiliary wings downwardly to

a point as indicated in Figure 2, or even slightly beyond that. This will give a decided upward thrust on the machine and by the angled mounting as indicated in Figure 10, a small component of the effort will be directed to moving the glider forwardly. This may be repeated several times in quick succession and under suitable conditions will be just sufficient extra raising effort to lift the glider off the ground.

A second condition will arise where the glider is in the air but launched in any conventional manner, and a period will be encountered where the air currents are not sufficient to enable the pilot to keep his glider in the air. Under these conditions the similar operation, as explained, is gone through and if the currents, plus the effort applied by the pilot are sufficient the glider may be easily kept aloft.

In other words, where there is just enough driving current in the air to keep the glider at a given elevation, manipulation of my auxiliary wings will enable the glider to gain elevation.

I wish it understood that I have not been able to fly a glider by means of manual effort thus applied, although I would not care to say the same cannot be done. The purpose of my invention is to supply at the times most desired enough extra lifting effort to carry out the operations as outlined.

The foregoing description and the accompanying drawings are believed to clearly disclose a preferred embodiment of my invention but it will be understood that this disclosure is merely illustrative and that such changes in the invention may be made as are fairly within the scope and spirit of the following claims:

What I claim is:

1. A glider propulsion device consisting of auxiliary wing members disposed below the fixed wings of a glider; said wings being pivoted at their adjacent ends to the glider body; a hand lever; a cross head disposed for vertical movement; guide for said cross head; linkage operatively connecting said cross head and both auxiliary wings; and linkage operatively connecting said cross head and the hand lever.

2. A glider propulsion device consisting of auxiliary wing members disposed below the fixed wings of a glider; said wings being pivoted at their adjacent ends to the glider body; and are provided with a plurality of shutters; a hand lever; a cross head disposed for vertical movement; guide for said cross head; linkage operatively connecting said cross head and both auxiliary wings; and linkage operatively connecting said cross head and the hand lever.

3. A glider propulsion device consisting of auxiliary wing members disposed below the fixed wings of a glider; said wings being

pivoted at their adjacent ends to the glider body; two hinge members adapted to secure the auxiliary wings to the glider body, said hinges disposed so as to converge to a point in front of the glider; a hand lever; a cross head disposed for vertical movement; guide for said cross head; linkage operatively connecting said cross head and both auxiliary wings; and linkage operatively connecting said cross head and the hand lever.

4. A glider propulsion device consisting of auxiliary wing members disposed below the fixed wings of a glider; said wings being pivoted at their adjacent ends to the glider body, and are provided with a plurality of shutters; a hand lever; a cross head disposed for vertical movement; guide for said cross head; linkage operatively connecting said cross head and both auxiliary wings; linkage operatively connecting said cross head and the hand lever; linkage secured to each shutter adapted to close all of the same at once and abutments secured to the fixed wings of the glider adapted to co-act with said shutter linkage to close the same when the auxiliary wings are raised to their upper limit.

5. A glider propulsion device consisting of auxiliary wing members disposed below the fixed wings of a glider; said wings being pivoted at their adjacent ends to the glider body, and are provided with a plurality of shutters; a hand lever; a cross head disposed for vertical movement; guide for said cross head; linkage operatively connecting said cross head and both auxiliary wings; linkage operatively connecting said cross head and the hand lever; linkage secured to each shutter adapted to close all of the same at once; abutments secured to the fixed wings of the glider adapted to co-act with said shutter linkage to close the same when the auxiliary wings are raised to their upper limit; and resilient means, each secured at one end to the glider body and at the other end to the auxiliary wings adapted to counterbalance the weight of the said wings.

In witness whereof, I hereunto subscribe my name this 28th day of August, A. D. 1930.

GUSTAV A. MILLER.
